UNITED STATES PATENT OFFICE.

ROBERT B. KUHN, OF CANTON, OHIO.

AIR-COOLED ENGINE.

1,307,680.

Specification of Letters Patent. Patented June 24, 1919.

Application filed January 8, 1919. Serial No. 270,198.

To all whom it may concern:

Be it known that I, ROBERT B. KUHN, a citizen of the United States, residing at Canton, in the county of Stark and State of Ohio, have invented certain new and useful Improvements in Air-Cooled Engines, of which the following is a specification.

The invention relates to means for cooling the cylinders of internal combustion engines by the movement of air; and one object of the improvement is to make the cooling means independent of the engine case or closure and also separate from the frame or hood of the machine for which the engine is used.

Further objects of the improvement are to give a greater range of heat control than has heretofore been provided; and to differentiate the amount of air passing the several cylinders of the engine.

These objects are attained by constructing a case forming a cooling chamber around the cylinders and a communicating vacuum chamber, by employing exhausting means for moving air to cool the engines when producing the highest heat, and providing a valved opening in the case between the cooling chamber and the exhausting means for varying the flow of air through the cooling chamber and a transverse diaphragm in the cooling chamber apertured for varying the flow of air past different cylinders.

An embodiment of the invention, as applied to a four cylinder automobile engine, is illustrated in the accompanying drawings, forming part hereof in which—

Figure 1 is a side elevation;

Fig. 2, a plan view;

Fig. 3, a longitudinal section on line 3—3,

Fig. 2;

Fig. 4, a plan section on line 4—4, Figs. 1 and 3.

Fig. 5, a plan section on line 5—5, Figs. 1 and 3.

Fig. 6, a transverse section on line 6—6, Figs. 1 to 5;

Fig. 7, a transverse section on line 7—7, Figs. 1 to 5; and

Fig. 8, a fragmentary section, showing details of the valved opening in the case of the vacuum chamber.

Similar numerals refer to similar parts throughout the drawings.

The engine cylinders 8 are mounted on the crank case 9, and the longitudinal radiating fins 10 are provided on the upper portion of

the cylinder wherein is located the combustion chamber 11, in accordance with the usual practice in air cooled automobile engines.

60

The case 12 of the cooling chamber 13 may be made with a reduced portion in the form of the open ended cylindric jackets 14 closely surrounding the edges of the radiating fins 10 throughout their length, and an enlarged portion 15 which may surround the cylinders below the fins.

65

The transverse diaphragm 16 is provided in the cooling case, and as shown, may be located in the enlarged lower portion thereof. A series of apertures 17 and 17^a are provided in the diaphragm around each of the cylinders and these apertures are so sized and spaced as to control and determine the amount or volume of air passing the respective cylinders.

70

For instance, if the operation of a particular cylinder, say the third cylinder as shown, habitually develops more heat than the others, some or all of the apertures 17^a around the same are made larger than those around the other cylinders, so that more air will pass this particular cylinder with a greater cooling effect than will pass the other cylinders.

75

The movement of air through the cooling case is preferably induced by a centrifugal fan 17^b exhausting from a vacuum chamber 18 formed by the case 19 mounted at the rear end of the crank case 9; and in the present embodiment, the air is drawn from the cooling chambers through the flues 20 in the saddle case formed by the walls 22 and 23 extending downward from the sides and bottom walls of the cooling chamber, on each side of the crank case.

80

It will be understood, that the use of such flues is not necessary when the vacuum chamber can communicate directly with the cooling chamber; and also that the use of a separate vacuum chamber is not necessary when the exhausting means can draw the air directly from the enlarged portion of the cooling chamber, which is in fact a common chamber which draws the air through the cooling flues formed by the cylinders, the fins and the surrounding jackets.

85

The capacity of the fan and the size of the various flues and chambers and the diaphragm apertures are designed for the movement of the required volume of air through the fin flues for cooling the cylin-

110

ders when the engine is operated under extraordinary or maximum heat producing conditions; and for regulating the movement of air for cooling the cylinders under the ordinary operating conditions, a valved opening is provided in the wall of the vacuum case at a point between the fin flues and the exhausting means.

Such opening may be in the form of a series of slots 24 in the tops of the vacuum chamber, which may be closed by the slotted valve or damper 25 for moving the maximum amount of air through the fin flues, and it is evident that by opening the slots 10 more or less by a shifting of the valve or damper, the amount of air passing through the fin flues will be reduced in proportion to the amount of air drawn through the valved opening.

20 I claim:—

1. In combination with the cylinders of an engine, a case forming a cooling chamber around the cylinders, means for moving air through the chamber, and a diaphragm in 25 the case having differential apertures for determining the amount of air passing through different portions of the chamber.

2. In combination with the cylinders of an engine, a case forming a cooling chamber around the cylinders, means for moving air through the chamber, and a diaphragm in 30 the case having differential apertures for determining the amount of air passing the several cylinders.

35 3. In combination with engine cylinders having radiating fins thereon, a case forming cooling flues among the fins and an enlarged cooling chamber at the end thereof, means for moving air through the cooling

flues and chamber, and a diaphragm in the 40 enlarged chamber having differential apertures for determining the amount of air passing the several cylinders.

4. In combination with the cylinders of an engine, a case forming cooling flues around 45 the cylinders and a vacuum chamber communicating therewith, and means for exhausting air from the vacuum chamber, there being a valved opening in the case between the cooling flues and the exhausting means 50 for regulating the flow of air through the cooling flues.

5. In combination with the cylinders of an engine, a case forming a cooling chamber around the cylinders and a vacuum chamber 55 communicating therewith, means for exhausting air from the vacuum chamber, there being a valved opening in the wall of the vacuum chamber.

6. In combination with the cylinder of an 60 engine, a case forming cooling flues around the cylinders and a common chamber communicating therewith, means for impelling air through the common chamber, there being a valved opening in the case between the 65 cooling flues and the impelling means for regulating the flow of air through the cooling flues.

7. In combination with the cylinder of an engine, a case forming cooling flues around 70 the cylinders and a common chamber communicating therewith, means for impelling air through the common chamber, and means between the cooling flues and the impelling means for regulating the amount of air 75 flowing through the cooling flues.

ROBERT B. KUHN.
